ABSTRACT

The present invention is directed to golf balls having surface textures with unique appearances and improved aerodynamic characteristics due, at least in part, to the use of curvilinear dimple plan shapes. In particular, the present invention is directed to a golf ball that includes at least a portion of its dimples having a plan shape defined by a number of convex or concave arcs that are derived from the vertices of a regular n-sided polygon, for example, an equilateral triangle or square.

CURVILINEAR GOLF BALL DIMPLES AND METHODS OF MAKING SAME

FIELD OF THE INVENTION

The present invention relates to golf ball dimples having a non-isodiametrical, curvilinear plan shape defined by circular arcs. In particular, the present invention relates to golf ball dimples having plan shapes defined by a number of convex or concave arcs derived from a regular n-sided polygon. When utilized on golf balls, the golf ball dimples of the present invention provide surface textures with unique appearances, while maintaining desirable aerodynamic characteristics.

BACKGROUND OF THE INVENTION

Golf balls generally include a spherical outer surface with a plurality of dimples formed thereon. The dimples on a golf ball improve the aerodynamic characteristics of a golf ball and, therefore, golf ball manufacturers have researched dimple patterns, shape, volume, and cross-section in order to improve the aerodynamic performance of a golf ball. Determining specific dimple arrangements and dimple shapes that result in an aerodynamic advantage requires an understanding of how a golf ball travels through air.

Aerodynamic forces acting on a golf ball are typically resolved into orthogonal components of lift (F_L) and drag (F_D). Lift is defined as the aerodynamic force component acting perpendicular to the flight path. It results from a difference in pressure that is created by a distortion in the air flow that results from the back spin of the ball. Due to the back spin, the top of the ball moves with the air flow, which delays the separation to a point further aft. Conversely, the bottom of the ball moves against the air flow, moving the separation point forward. This asymmetrical separation creates an arch in the flow pattern, requiring the air over the top of the ball to move faster, and thus have lower pressure than the air underneath the ball.

Drag is defined as the aerodynamic force component acting opposite to the ball flight direction. As the ball travels through the air, the air surrounding the ball has different velocities and, thus, different pressures. The air exerts maximum pressure at the stagnation point on the front of the ball. The air then flows over the sides of the ball and has increased velocity and reduced pressure. The air separates from the surface of the ball, leaving a large turbulent flow area with low pressure, i.e., the wake. The difference between the high pressure in front of the ball and the low pressure behind the ball reduces the ball speed and acts as the primary source of drag.

Lift and drag, among other aerodynamic characteristics of a golf ball, are influenced by the external surface geometry of the ball, which includes the dimples thereon. As such, the dimples on a golf ball play an important role in controlling those parameters.

Recently, a number of golf ball products in the market place have been introduced with golf ball surfaces featuring visually distinct dimple patterns. Golf balls featuring these visually distinct dimple patterns are most prevalent in the premium distance category. Existing examples of such golf balls include, but are not limited to, the Dunlop XXiO XD Aero, the Bridgestone Tourstage PHYZ, and the Saso Kaede. While these golf ball designs possess a unique visual appearance, the dimple patterns utilized on the golf balls, when compared to conventional dimple patterns, are less aerodynamically efficient.

2

Other unique dimple designs have also been introduced. For example, isodiametrical dimples, such as those disclosed in U.S. Pat. No. 5,377,989, provide for visually distinct dimple shapes. However, due to the nature of the curvatures in forming the isodiametric shape, these dimples limit surface coverage uniformity and packing efficiency when utilized on golf balls. Accordingly, there remains a need for a dimple geometry that provides a visually distinct golf ball surface texture, while providing improved aerodynamic characteristics and maximized packing efficiency.

SUMMARY OF THE INVENTION

The present invention is directed to a golf ball having a substantially spherical surface, including a plurality of dimples on the spherical surface, wherein at least a portion of the plurality of dimples, for example, about 50 percent or more, include a curvilinear plan shape defined by at least 3 circular arcs, wherein each circular arc includes two endpoints that define adjacent vertices of a regular polygon. In one embodiment, the curvilinear plan shape is defined by 3 to 12 circular arcs. In another embodiment, the regular polygon is an equilateral polygon comprising from 3 to 12 sides. In still another embodiment, the number of circular arcs is equivalent to the number of sides of the regular polygon. The circular arcs may include concave arcs, convex arcs, or combinations thereof. For example, the plan shape may be defined by an even number of alternating convex and concave circular arcs less than or equal to 12. In yet another embodiment, the portion of the plurality of dimples has a plan shape area ratio of about 0.35 to about 1.75.

The present invention is also directed to a golf ball having a substantially spherical surface, including a plurality of dimples on the spherical surface, wherein at least a portion of the plurality of dimples, for example, about 70 percent or more, include a curvilinear plan shape defined by a plurality of arc segments having endpoints that define adjacent vertices of a polygon including n sides, wherein each arc segment includes an arc center outside of the polygon, and wherein the plurality of arc segments is equal to n. In one embodiment, n ranges from 3 to 12, and more preferably, from 3 to 8. In another embodiment, the plurality of arc segments has identical lengths and radii. Conversely, the arc segments may each have a different length and radius. In still another embodiment, the plurality of arc segments includes both concave and convex circular arcs. For example, the plan shape may be defined by alternating convex and concave circular arcs. In yet another embodiment, the portion of the plurality of dimples has a plan shape perimeter ratio of less than 1.10.

The present invention is further directed to a golf ball dimple having a perimeter defined by a plurality of convex or concave circular arcs having identical lengths and radii, wherein each circular arc has two endpoints that define consecutive vertices of a regular n-sided polygon. In one embodiment, the perimeter of the dimple is defined by at least 3 circular arcs, for example, 3 to 12 circular arcs. In this aspect, the perimeter may be defined by a plurality of concave circular arcs and a plurality of convex circular arcs. In another embodiment, the regular n-sided polygon is selected from the group consisting of triangles, squares, pentagons, hexagons, heptagons, octagons, nonagons, decagons, hendecagons, and dodecagons.

The present invention may also be directed to a golf ball having a substantially spherical surface, including a plurality of dimples on the spherical surface, wherein at least a

portion of the plurality of dimples include a convex curvilinear plan shape defined by circular arcs, wherein each circular arc comprises two endpoints that define adjacent vertices of a regular polygon having three or four sides, for example, an equilateral triangle or a square, wherein each vertex of the regular polygon has an arc vertex angle θ_v , defined by the following equation:

$$180 \cdot \left(\frac{n-2}{n} \right) < \theta_v < 180 \cdot \left(\frac{n-2}{n} \right) + R$$

wherein n is the number of sides of the regular polygon and R is about 5 to 35. In one embodiment, each circular arc comprises an arc center outside of the regular polygon. In another embodiment, each side of the regular polygon is about 0.085 inches to about 0.350 inches in length. In still another embodiment, the regular polygon has an inradius of about 0.025 inches to about 0.100 inches and a circumradius of about 0.050 inches to about 0.200 inches.

The present invention is further directed to a golf ball having a substantially spherical surface, including a plurality of dimples on the spherical surface, wherein at least a portion of the plurality of dimples include one or more non-isodiametrical plan shapes, wherein each non-isodiametrical plan shape is defined by a plurality of convex arc segments having endpoints that define adjacent vertices of a regular polygon comprising n sides, wherein the plurality of arc segments is equal to n, wherein n is three or four, wherein each vertex of the regular polygon has an arc vertex angle θ_v , defined by the following equation:

$$180 \cdot \left(\frac{n-2}{n} \right) < \theta_v < 180 \cdot \left(\frac{n-2}{n} \right) + R$$

where n is the number of sides of the regular polygon and R is about 5 to 35, and wherein each arc segment includes an arc center outside of the regular polygon. In one embodiment, each dimple has a plan shape perimeter ratio of less than 1.10. In another embodiment, in the portion of the plurality of dimples, each dimple has a plan shape area of about 0.0025 in² to about 0.045 in². In still another embodiment, in the portion of the plurality of dimples, each dimple has a plan shape area ratio of greater than 1 and less than 1.75. In yet another embodiment, in the portion of the plurality of dimples, each dimple has a maximum absolute distance of about 0.0005 inches to about 0.040 inches. In another embodiment, in the portion of the plurality of dimples, a first number of dimples include a non-isodiametrical plan shape defined by a plurality of convex arc segments having endpoints that define adjacent vertices of a polygon including three sides and a second number of dimples include a non-isodiametrical plan shape defined by a plurality of convex arc segments having endpoints that define adjacent vertices of a polygon including four sides. In this aspect, the first number of dimples and the second number of dimples may have different plan shape perimeter ratios and different plan shape areas. In yet another embodiment, each arc segment has the same radius.

The present invention may also be directed to a golf ball dimple having a non-isodiametrical plan shape defined by a plurality of convex circular arcs, wherein each circular arc has a pair of endpoints that define consecutive vertices of a regular three-sided or four-sided polygon, wherein each circular arc includes an arc center outside of the polygon,

wherein each pair of endpoints define consecutive vertices on the same polygon, and wherein each vertex of the polygon has an arc vertex angle θ_v , defined by the following equation:

$$180 \cdot \left(\frac{n-2}{n} \right) < \theta_v < 180 \cdot \left(\frac{n-2}{n} \right) + R$$

where n is the number of sides of the regular polygon and R is about 5 to 35. In one embodiment, the golf ball dimple has an equivalent dimple diameter of about 0.080 inches to about 0.220 inches. In another embodiment, the golf ball dimple has a plan shape area of about 0.005 in² to about 0.035 in². In still another embodiment, the golf ball dimple has a dimple surface volume of about 0.5×10^{-4} in³ to about 3.0×10^{-4} in³. In yet another embodiment, the regular polygon has a circumradius and an inradius, and wherein each circular arc has a radius at least twice the circumradius of the regular polygon. In still another embodiment, the regular polygon has an inradius of about 0.025 inches to about 0.100 inches and a circumradius of about 0.050 inches to about 0.200 inches.

The present invention is also directed to a golf ball having a substantially spherical surface, including a plurality of dimples on the spherical surface, wherein at least a portion of the plurality of dimples include a non-isodiametrical plan shape defined by at least three circular arcs, wherein each circular arc defines an edge of the dimple and includes two discontinuous endpoints that define adjacent vertices of a base polygon, wherein at least one dimple pair in the portion of the plurality of dimples includes a first dimple having a first edge and a second dimple having a second edge that is adjacent to the first edge, and wherein the first edge is defined by a concave circular arc and the second edge is defined by a convex circular arc, and the maximum integration distance between the first edge and the second edge is about 0.020 inches or less. In another embodiment, the first edge and the second edge have substantially equal arc edge radii. In still another embodiment, the first edge and the second edge each have a maximum distance between the circular arc and the base polygon of about 0.005 inches to about 0.030 inches. In one embodiment, the first edge and the second edge have the same maximum distances. In another embodiment, the first edge has a first maximum distance, the second edge has a second maximum distance, and the difference between the first maximum distance and the second maximum distance is less than or equal to about 0.01 inches. In yet another embodiment, the maximum integration distance between the first edge and the second edge is about 0.010 inches or less. In another embodiment, the at least a portion of the plurality of dimples include a non-isodiametrical plan shape defined by three or four circular arcs.

The present invention is further directed to a golf ball having a substantially spherical surface, including a plurality of dimples on the spherical surface, wherein at least a portion of the plurality of dimples include a non-isodiametrical plan shape defined by at least three circular arcs, wherein each circular arc defines an edge of the dimple and includes two discontinuous endpoints that define adjacent vertices of a regular polygon, wherein at least one dimple in the portion of the plurality of dimples includes at least one edge that is adjacent to a respective edge of at least one other dimple in the portion of the plurality of dimples, wherein the at least one edge has a first concavity, the respective edge has a

second concavity, and the first concavity is different from the second concavity, wherein the maximum integration distance between the at least one edge and the respective edge is about 0.020 inches or less, and wherein the at least one edge and the respective edge are unified. In one embodiment, the at least one edge and the respective edge have substantially equal arc edge radii. In another embodiment, the first concavity and the second concavity are selected from concave-in or concave-out. For example, the first concavity may be concave-in and the second concavity may be concave-out. In still another embodiment, the maximum integration distance between the first edge and the second edge is about 0.010 inches or less, for instance, about 0.005 inches or less. In yet another embodiment, at least about 25 percent, for example, at least about 50 percent, of the dimples on the golf ball include at least one unified edge.

The present invention may also be directed to a golf ball having a substantially spherical surface, including a plurality of dimples on the spherical surface, wherein at least a portion of the plurality of dimples include a non-isodiametrical plan shape defined by at least three circular arcs, wherein each circular arc defines an edge of the dimple and includes two discontinuous endpoints that define adjacent vertices of a regular polygon, wherein at least one dimple in the portion of the plurality of dimples includes at least two edges that are adjacent to respective edges of at least two other dimples in the portion of the plurality of dimples, wherein the at least two edges each have a first concavity, the respective edges of the at least two other dimples each have a second concavity, and the first concavity is different from the second concavity, wherein the maximum integration distance between each of the at least two edges and the respective edges is about 0.010 inches or less, and wherein the at least two edges and the respective edges are unified. In this aspect, the first concavity and the second concavity are selected from concave-in or concave-out. In another embodiment, at least about 50 percent of the dimples on the golf ball include at least two unified edges. In yet another embodiment, at least about 10 percent, for instance, at least about 50 percent, of the edges defined by circular arcs are unified.

BRIEF DESCRIPTION OF THE DRAWINGS

Further features and advantages of the invention can be ascertained from the following detailed description that is provided in connection with the drawings described below:

FIG. 1 is a flowchart illustrating the steps according to a method of forming a dimple plan shape of the present invention;

FIG. 2 illustrates a regular polygon defined in a two-dimensional plane according to one embodiment of the present invention;

FIG. 3 illustrates a defined first convex arc segment and associated center point of the regular polygon of FIG. 2 according to one embodiment of the present invention;

FIG. 4A illustrates all defined convex arc segments and associated center points of the regular polygon of FIG. 2 according to one embodiment of the present invention;

FIG. 4B illustrates all defined arc segments of FIG. 4A as convex arcs according to one embodiment of the present invention;

FIG. 5 illustrates a dimple plan shape constructed from the arc segments of FIG. 4A-B according to one embodiment of the present invention;

FIG. 6 illustrates a defined first concave arc segment and associated center point of the regular polygon of FIG. 2 according to one embodiment of the present invention;

FIG. 7A illustrates all defined concave arc segments and associated center points of the regular polygon of FIG. 2 according to one embodiment of the present invention;

FIG. 7B illustrates all defined arc segments of FIG. 7A as concave arcs according to one embodiment of the present invention;

FIG. 8 illustrates a dimple plan shape constructed from the arc segments of FIG. 7A-B according to one embodiment of the present invention;

FIGS. 9-11 illustrate various embodiments of golf ball dimple patterns constructed from a plurality of dimple plan shapes according to the present invention;

FIG. 12A is a graphical representation illustrating dimple surface volumes for golf balls produced in accordance with the present invention;

FIG. 12B is a graphical representation illustrating preferred dimple surface volumes for golf balls produced in accordance with the present invention;

FIG. 13 illustrates a golf ball dimple plan shape defined by concave arcs that are created from the vertices of a regular 5-sided polygon according to one embodiment of the present invention;

FIG. 14 illustrates a golf ball dimple plan shape defined by convex arcs that are created from the vertices of a regular 6-sided polygon according to one embodiment of the present invention;

FIG. 15 illustrates a golf ball dimple plan shape defined by a random arrangement of convex and concave arcs that are created from the vertices of a regular 5-sided polygon according to one embodiment of the present invention;

FIG. 16 illustrates a golf ball dimple plan shape defined by alternating convex and concave arcs that are created from the vertices of a regular 6-sided polygon according to one embodiment of the present invention;

FIG. 17 illustrates a golf ball dimple plan shape defined by convex arcs having different radii that are created from the vertices of a regular 4-sided polygon according to one embodiment of the present invention;

FIG. 18 illustrates a golf ball dimple plan shape according to one embodiment of the present invention;

FIG. 19 illustrates a golf ball dimple plan shape according to another embodiment of the present invention;

FIGS. 20 and 21 illustrate various embodiments of golf ball dimple patterns constructed from a plurality of dimple plan shapes according to the present invention;

FIG. 22 is a graphical representation illustrating preferred dimple surface volumes for golf balls produced in accordance with one embodiment of the present invention;

FIGS. 23 and 24 illustrate various dimple base patterns having plan shapes contemplated by the present invention;

FIG. 25 shows a dimple pair according to one embodiment of the present invention where adjacent edges are unified and have opposite concavity;

FIGS. 26A and 26B show an arrangement of four dimples having the disclosed plan shapes and unified edges according to one embodiment of the present invention;

FIG. 27 illustrates a dimple pattern having cohesively integrated dimples according to one embodiment of the present invention;

FIGS. 28A and 28B show an arrangement of four dimples having the disclosed plan shapes and unified edges according to another embodiment of the present invention; and

FIG. 29 illustrates a dimple pattern having cohesively integrated dimples according to another embodiment of the present invention.

DETAILED DESCRIPTION OF THE INVENTION

The present invention is directed to golf balls having surface textures with unique appearances and improved aerodynamic characteristics due, at least in part, to the use of noncircular dimple plan shapes. In particular, the present invention is directed to a golf ball that includes at least a portion of its dimples having a curvilinear plan shape defined by a number of convex or concave arcs that are derived from a regular n-sided polygon.

Advantageously, in one embodiment, golf balls including dimple plan shapes produced in accordance with the present invention have visually distinct surface textures. Indeed, the dimple plan shapes of the present invention possess a unique visual appearance. In another embodiment, the dimple plan shapes of the present invention allow the dimples to be arranged according to spherically tiled dimple designs. The spherical tiling layouts utilizing the dimple plan shapes of the present invention provide improved symmetry including multiple axes of symmetry on each golf ball. As a result, golf balls including the dimple plan shapes of the present invention exhibit improved aerodynamic performance in addition to providing visually distinct dimple patterns.

Dimple Plan Shape

A dimple plan shape, as used herein, refers to the perimeter of the dimple as seen from a top view of the dimple, or the demarcation between the dimple and the outer surface of the golf ball or fret surface. The present invention contemplates dimples having a curvilinear plan shape.

The present invention contemplates curvilinear dimple plan shapes defined by circular arcs that form a simple closed path. A “simple closed path,” as used herein, includes a curve that starts and ends at the same point without traversing any defining point or edge along the path more than once. In particular, the dimple plan shapes of the present invention include a number of convex or concave circular arcs having endpoints that define the vertices of a regular n-sided polygon. That is, the plan shapes of the present invention are defined by arc segments created from a regular n-sided polygon. Indeed, the present invention contemplates non-smooth plan shapes having discontinuities at the endpoints of each arc segment. As used herein, a plan shape has “discontinuities at the endpoints” or “discontinuous endpoints” if two dimple edges meet at a point making the plan shape non-differentiable at that point.

The present invention contemplates plan shapes defined by a plurality of arc segments that are derived from the sides of a regular n-sided polygon. In one embodiment, the arc segments are created by arcs of circles centered outside of a regular polygon. As discussed in greater detail below, the location of the centers of the circles is dependent on whether the number of sides of the polygon is odd or even. For example, when the number of sides of the polygon is even, the centers of the circles lie on an axis defined by the center of the polygonal inradius and the side mid-point. In another embodiment, when the number of sides of the polygon is odd, the centers of the circles lie on an axis defined by the center of the polygonal inradius and the vertex. Indeed, the circular arcs are designed to sweep the sides of the regular polygon such that arc segments are created between each vertex of the regular polygon in a convex or concave manner.

In one embodiment, the plan shape may be defined by a plurality of convex arcs. For example, the plan shape may include a plurality of arc segments that curve in an outwardly direction. In another embodiment, the plan shape may be defined by a plurality of concave arcs. For example, the plan shape may include a plurality of arc segments that curve in an inwardly direction.

In still another embodiment, the plan shape may be defined by a combination of convex and concave arcs. For example, the plan shape may include one or more convex arcs and one or more concave arcs such that each arc segment is created between each vertex of the regular polygon in a concave or convex manner.

In yet another embodiment, the plan shape may be defined by alternating convex and concave arcs. For example, the plan shape may include a plurality of arc segments that alternate between convex arcs and concave arcs. In this embodiment, the number of sides of the polygon is even.

The number of arc segments is equivalent to the number of sides of the regular polygon. For example, a plan shape including three arc segments may correspond to a three-sided polygon or a triangle. In another embodiment, a plan shape including four arc segments may correspond to a four-sided polygon or a square. In still another embodiment, a plan shape including five arc segments may correspond to a five-sided polygon or a pentagon. In yet another embodiment, a plan shape including six arc segments may correspond to a six-sided polygon or a hexagon.

In this aspect, the present invention contemplates the use of any regular n-sided polygon. By the term, “regular n-sided polygon,” it is meant a polygon that is equiangular (i.e., all angles are equal in measure) and equilateral (i.e., all sides have the same length). In one embodiment, the present invention contemplates regular n-sided polygons, where n is equal to or greater than 3. Indeed, the present invention contemplates regular polygons having at least 3 or more equal length sides. While polygons having a higher number of sides may be employed, increasing the number of sides produces plan shapes which closely approximate a circular perimeter. Thus, it is preferable to utilize polygons having smaller values of n.

For example, the present invention contemplates the use of regular n-sided polygons having from 3 to about 50 equal length sides. In another embodiment, the polygon of the present invention has from 3 to about 26 equal length sides. In still another embodiment, the polygon of the present invention has from 3 to about 12 equal length sides. In yet another embodiment, the polygon of the present invention has from 3 to about 8 equal length sides. For example, the polygon may have 4 equal length sides.

Suitable examples of regular n-sided polygons contemplated by the present invention include, but are not limited to, triangles, squares, pentagons, hexagons, heptagons, octagons, nonagons, decagons, hendecagons, and dodecagons. In one embodiment, the regular n-sided polygon is a triangle. In another embodiment, the regular n-sided polygon is a square.

The overall dimensions of the regular n-sided polygon may vary. In this aspect, the dimensions of the polygon may be defined by the length of the sides of the polygon. As noted above, the polygons of the present invention are equilateral (i.e., all sides have the same length). In this aspect, the length of each side of the polygon may be at least about 0.085 inches. In one embodiment, the length of each side of the polygon is about 0.350 inches or less. For example, the length of each side of the polygon may range from about 0.085 inches to about 0.350 inches. In another embodiment,

the length of each side of the polygon ranges from about 0.085 inches to about 0.260 inches. For example, the length of each side may range from about 0.100 inches to about 0.250 inches. In another embodiment, the length of each side may range from about 0.125 inches to about 0.225 inches. In still another embodiment, the length of each side may range from about 0.150 inches to about 0.200 inches.

In another embodiment, the dimensions of the polygon may be defined by the inradius of the regular polygon. For purposes of the present invention, the term, "inradius," refers to the radius of a polygon's incircle, or the radius of the largest circle that fits inside of the polygon and is tangent to each side. The inradius of a regular polygon with n sides and side length a is given by equation (1), denoted below:

$$r = \frac{1}{2}a \cot\left(\frac{\pi}{n}\right). \quad (1)$$

In this aspect, the present invention contemplates regular polygons having an inradius of at least about 0.020 inches. In one embodiment, the inradius is about 0.175 inches or less. In another embodiment, the inradius is about 0.125 inches or less. In yet another embodiment, the inradius is about 0.115 inches or less. In still another embodiment, the inradius is about 0.010 inches or less. For example, the inradius may range from about 0.025 inches to about 0.150 inches. In one embodiment, the polygon of the present invention has an inradius of about 0.050 inches to about 0.125 inches. In another embodiment, the polygon of the present invention has an inradius of about 0.075 inches to about 0.115 inches. In still another embodiment, the polygon of the present invention has an inradius of about 0.080 inches to about 0.100 inches. For example, the polygon of the present invention may have an inradius of about 0.025 inches to about 0.100 inches.

In still another embodiment, the dimensions of the polygon may be defined by the circumradius of the regular polygon. For purposes of the present invention, the term, "circumradius," refers to the radius of the polygon's circumcircle, or the radius of the circle that passes through each vertex of the regular polygon. Indeed, the circumradius will approach the inradius as n approaches infinity. For example, when $n=3$, the circumradius is twice the inradius.

In this aspect, the present invention contemplates regular polygons having a circumradius of at least about 0.05 inches. Likewise, the circumradius may be about 0.300 inches or less. In one embodiment, the circumradius ranges from about 0.050 inches to about 0.300 inches. For example, the polygon of the present invention may have a circumradius of about 0.075 inches to about 0.275 inches. In another embodiment, the polygon of the present invention may have a circumradius of about 0.100 inches to about 0.250 inches. In still another embodiment, the polygon of the present invention may have a circumradius of about 0.125 inches to about 0.225 inches. In yet another embodiment, the polygon of the present invention may have a circumradius of about 0.150 inches to about 0.200 inches. For example, the polygon of the present invention may have a circumradius of about 0.050 inches to about 0.200 inches.

The length and radii of the curvature of each arc segment will vary based on the selected dimensions of the regular n -sided polygon. However, in one embodiment, the arc segments of the plan shape have equal curvatures. That is, each arc segment of the plan shape has an identical length and radii. In another embodiment, the arc segments of the

plan shape have different lengths and radii. For instance, each arc segment may have a different radii. In still another embodiment, at least one of the arc segments may have different radii.

FIG. 1 illustrates one embodiment of a method of forming a dimple plan shape in accordance with the present invention. For example, step 101 includes selecting the regular polygon and its overall dimensions, and defining the regular polygon in a two-dimensional plane. Indeed, any of the regular n -sided polygons discussed above are contemplated in this aspect of the present invention. In one embodiment, the dimensions of the regular polygon may be defined by specifying the length of each side of the polygon. In another embodiment, the dimensions of the polygon may be defined by specifying the inradius or circumradius of the regular polygon. However, the dimensions of the polygon, including the length of each side, the inradius, and the circumradius, should be selected such that the values are in accordance with the parameters discussed above. FIG. 2 illustrates a regular polygon defined in a two-dimensional plane. As shown in FIG. 2, the regular polygon 5 has four equal sides that meet at four vertices, V_1, V_2, V_3 , and V_4 . The four-sided polygon 5 is referred to, hereinafter, as a square.

Once the base polygon is chosen, each arc segment is constructed. According to the present invention, the number of arc segments is equivalent to the number of sides of the regular polygon. For example, if the regular polygon has four sides, the plan shape of the present invention will be defined by four arc segments. To construct the first arc segment, an arc center is determined (step 102). The arc center, C , may be defined as any point lying outside the polygonal boundary. Indeed, each arc center should lie outside the convex hull of the base polygon.

In this aspect, the location of the arc center, C , will vary depending on the number of sides of the polygon. In one embodiment, when the number of sides of the polygon is even, the arc center lies on an axis that extends radially from the inradius center and bisects the opposing side of the polygon. In another embodiment, when the number of sides of the polygon is odd, the arc center lies on an axis that extends radially from the inradius center and through the opposing vertex. For example, if the polygon is a triangle, the arc centers lie on axes defined by the inradius center and the opposing vertex. In contrast, if the polygon is a square, the arc centers lie on axes defined by the inradius center and the opposing side mid-point.

After the arc center has been defined, at step 103, an arc is swept around the arc center to create a circle. In one embodiment, the circle should sweep one side of the regular polygon such that an arc segment is defined having endpoints at two consecutive vertices of the polygon. In this regard, to ensure that the circle sweeps the interior or exterior of a side of the polygon, the radius, r , of the circle should, at a minimum, be greater than twice the circumradius, r_c , of the selected polygon. For example, the radius, r , of the circle should satisfy the following inequality, denoted as equation (2) below:

$$2r_c < r < 2r_c * \left(\frac{\alpha * \sin(\pi/n)}{\sqrt{n^\beta}} + 1 \right), \quad (2)$$

where constants, α and β , define the upper bound on the radius. In one embodiment, α is a value between about 50 and about 100, while β is a value between about 2 and about 4. For example, α may be between about 60 and about 90.

In one embodiment, α is between about 75 and about 85. In another embodiment, α is between about 50 and 65. In yet another embodiment, α is between about 85 and 100.

FIG. 3 demonstrates a defined first arc segment and associated center point using the square 5 as the regular polygon. For example, the arc center, C1, is defined as a point lying outside the boundary of the square 5. The radius, r_1 , of the circle, A1, is determined such that the radius is at least twice the circumradius of the square 5 and satisfies the inequality of equation (2). The circle, A1, is swept around the arc center, C1, such that the circle sweeps one side of the square 5. As a result, arc segment, S1, is defined such that its endpoints are at consecutive vertices, V_1 and V_2 , of the square 5.

Steps 102 and 103, as described above, are repeated for each arc segment of the plan shape (step 104). Indeed, an arc segment should be constructed for each side of the selected regular polygon. In this aspect, the remaining arc centers should be defined around the regular polygon such that each side of the polygon is utilized in constructing an arc segment.

For example, FIG. 4A shows all four defined arc segments and associated center points of the square 5. As shown in FIG. 4A, the arc center, C2, is defined as a point lying outside the boundary of the square polygon. The radius, r_2 , of the circle, A2, is determined such that the radius is at least twice the circumradius of the square 5 and satisfies the inequality of equation (2). The circle, A2, is swept around the arc center, C2, to define arc segment, S2, having endpoints at consecutive vertices, V_2 and V_3 , of the square.

Similarly, the arc center, C3, is defined as a point lying outside the boundary of the square polygon. The radius, r_3 , of the circle, A3, is determined such that the radius is at least twice the circumradius of the square 5 and satisfies the inequality of equation (2). The circle, A3, is swept around the arc center, C3, to define arc segment, S3, having endpoints at consecutive vertices, V_3 and V_4 , of the square.

Further, arc center, C4, is defined as a point lying outside the boundary of the square polygon. The radius, r_4 , of the circle, A4, is determined such that the radius is at least twice the circumradius of the square 5 and satisfies the inequality of equation (2). The circle, A4, is swept around the arc center, C4, to define arc segment, S4, having endpoints at consecutive vertices, V_4 and V_1 , of the square. In this embodiment, the circles, the radii, the arc segments, and the Euclidean distance of the arc centers from the incenter of the polygon, are equivalent.

As discussed briefly above, the arc segments of the present invention may be convex or concave. In this aspect of the invention, the location of the arc center relative to the arc will determine whether the arc segment is convex or concave. For example, when forming a convex arc, the arc center should lie on the side opposite to the side of the polygon where the convex arc segment is formed. Conversely, when forming a concave arc, the arc center should lie on the same side as the side of the polygon where the concave arc segment is formed.

FIGS. 2-4B demonstrate the use of convex arc segments. Indeed, FIG. 3 shows the arc center C1 positioned on the side opposite to the side of the polygon where the convex arc segment will be formed (i.e., between V1 and V2). FIG. 4B exemplifies arc segments, S1-S4, as convex arcs.

After each of the arc segments are constructed, the dimple plan shape of the present invention is generated (step 105). FIG. 5 shows the final dimple plan shape constructed from arc segments, S1-S4, defined in FIG. 4B. In particular, FIG. 5 illustrates a curvilinear dimple plan shape 10 (represented

by bold line) contemplated by the present invention. Specifically, FIG. 5 shows a convex dimple plan shape defined by circular arc segments and created from a square (4-sided polygon). As can be seen by the constructed curvilinear dimple plan shape of FIG. 5, the present invention contemplates non-smooth plan shapes having discontinuities at the endpoints of each arc segment. Indeed, the discontinuity at each end point is maintained after constructing the arcs such that the resulting plan shape is non-isodiametrical in nature.

In certain embodiments, the present invention contemplates dimple plan shapes defined by convex arc segments and created from a square, such as the plan shape depicted in FIG. 5. In other embodiments, the dimple plan shapes are defined by convex arc segments and created from a triangle, such as the plan shape depicted in FIG. 18. In this aspect of the invention, the square and triangular convex dimple plan shapes may be formed from equilateral polygons having any of the side lengths, inradius values, and circumradius values discussed above. However, in one embodiment, the square and triangular convex dimple plan shapes may be formed from squares and triangles, respectively, having an inradius of about 0.025 inches to about 0.100 inches. In another embodiment, the inradius may be about 0.025 inches to about 0.085 inches. For instance, the squares and triangles may have an inradius of about 0.045 inches to about 0.075 inches. Similarly, the square and triangular convex dimple plan shapes may be formed from squares and triangles, respectively, having a circumradius of about 0.050 inches to about 0.200 inches. In one embodiment, the square and triangles may have a circumradius of about 0.075 inches to about 0.150 inches. In another embodiment, the circumradius is about 0.06 inches to about 0.130 inches. In yet another embodiment, the circumradius is about 0.09 inches to about 0.125 inches.

The dimple plan shapes of the present invention also maintain a maximum absolute distance or sagitta. For example, the square and triangular convex dimple plan shapes maintain a maximum absolute distance or sagitta. As used herein, the "maximum absolute distance" or "sagitta" is defined as the maximum distance between any point on the plan shape and the base polygon. FIG. 18 shows a triangular convex dimple plan shape produced in accordance with the present invention. As shown in FIG. 18, the maximum absolute distance between the polygon (triangle) and the farthest point on the plan shape from the polygonal boundary is represented by d_{max} . The distance d may be calculated according to the following equation:

$$d = \sqrt{(x_{\text{polygon}} - x_{\text{plan}})^2 + (y_{\text{polygon}} - y_{\text{plan}})^2}$$

The maximum value, the sagitta, for all sides of the polygon is the maximum absolute distance d_{max} . In one embodiment, d_{max} is at least about 0.0005 inches. In another embodiment, d_{max} is at least about 0.001 inches. In yet another embodiment, d_{max} is at least about 0.003 inches. In still another embodiment, d_{max} is about 0.040 inches or less. In yet another embodiment, d_{max} is about 0.03 inches or less. In still another embodiment, d_{max} is about 0.020 inches or less. For example, the maximum absolute distance, d_{max} , or sagitta, may range from about 0.0005 inches to about 0.040 inches. In another embodiment, the maximum absolute distance, d_{max} , or sagitta, ranges from about 0.001 inches to about 0.030 inches. In still another embodiment, the maximum absolute distance, d_{max} , or sagitta, ranges from about 0.003 inches to about 0.020 inches.

Furthermore, the convex dimple plan shapes of the present invention include an arc vertex angle. For instance, each of the square and triangular convex dimple plan shapes

constructed in accordance with the present invention includes an arc vertex angle. As used herein, "arc vertex angle," is defined as the angle formed by tangent lines drawn through the shared vertex of adjacent arc segments of the plan shape. For instance, as shown in FIG. 19, the curvilinear dimple plan shape 10 of FIG. 5 has an arc vertex angle θ_v . The arc vertex angle θ_v is the angle formed by tangent line T1 and tangent line T2 drawn through the shared vertex V4 of adjacent arc segments S1 and S2. The arc vertex angle θ_v may be defined by the following equation:

$$180 \cdot \left(\frac{n-2}{n} \right) < \theta_v < 180 \cdot \left(\frac{n-2}{n} \right) + R$$

where n is the number of sides of the regular polygon, R is a constant, and θ_v is the arc vertex angle. In one embodiment, R has a value of about 5 to 35, for example, about 5 to 30, about 10 to 25, about 10 to 20, and about 15 to 20. In this aspect, the arc vertex angle for a triangle may range from greater than 60° to less than 95°, for instance, from 65° to 85° or from 70° to 80°. Similarly, the arc vertex angle for a square may range from greater than 90° to less than 125°, for example, from 95° to 120° or from 100° to 115°.

The process described above in FIG. 1 is also applicable to forming a dimple plan shape having concave arc segments. For example, steps 102-105 may be adjusted for the concave nature of the arc. FIGS. 6-8, discussed in more detail below, exemplify the process of FIG. 1 for forming dimple plan shapes having concave arc segments in accordance with the present invention.

As discussed above, step 101 includes selecting the regular polygon and its overall dimensions, and defining the regular polygon in a two-dimensional plane. For illustrative purposes, the square 5 having four equal sides that meet at four vertices, V₁, V₂, V₃, and V₄ (as shown in FIG. 2) will be used.

To construct the first arc segment, an arc center is determined (step 102). In this embodiment, since the number of sides of the polygon is even, the arc center should lie on an axis that extends radially from the polygonal incenter and through the vertex. Additionally, because a concave arc segment is contemplated, the arc center should lie on the same side as the side of the polygon where the concave arc segment is formed. For example, as shown in FIG. 6, the arc center C1 lies on the same side as the side of the polygon where the first concave arc segment will be formed (i.e., between V1 and V2).

FIG. 6 demonstrates a defined first concave arc segment and associated center point using the square 5 as the regular polygon. For example, the arc center, C1, is defined as a point lying outside the boundary of the square 5, but on the same side of S1. The radius, r₁, of the circle, A1, is determined such that the radius is at least twice the circumradius of the square 5 and satisfies the inequality of equation (2). The circle, A1, is swept around the arc center, C1, such that the circle sweeps one side of the square 5. As a result, concave arc segment, S1, is defined such that its endpoints are at consecutive vertices, V₁ and V₂, of the square 5.

Steps 102 and 103, as described above, are repeated for each arc segment of the plan shape (step 104). Indeed, an arc segment should be constructed for each side of the selected regular polygon. In this aspect, the remaining arc centers should be defined around the regular polygon such that each side of the polygon is utilized in constructing an arc segment. For example, FIG. 7A shows all four defined concave

arc segments and associated center points of the square 5. As shown in FIG. 7A, the arc center, C2, is defined as a point lying outside the boundary of the square polygon, but located on the same side as S2. The radius, r₂, of the circle, A2, is determined such that the radius is at least twice the circumradius of the square 5 and satisfies the inequality of equation (2). The circle, A2, is swept around the arc center, C2, to define arc segment, S2, having endpoints at consecutive vertices, V₂ and V₃, of the square.

Similarly, the arc center, C3, is defined as a point lying outside the boundary of the square polygon, but located on the same side as S3. The radius, r₃, of the circle, A3, is determined such that the radius is at least twice the circumradius of the square 5 and satisfies the inequality of equation (2). The circle, A3, is swept around the arc center, C3, to define arc segment, S3, having endpoints at consecutive vertices, V₃ and V₄, of the square.

Further, arc center, C4, is defined as a point lying outside the boundary of the square polygon, but located on the same side as S4. The radius, r₄, of the circle, A4, is determined such that the radius is at least twice the circumradius of the square 5 and satisfies the inequality of equation (2). The circle, A4, is swept around the arc center, C4, to define arc segment, S4, having endpoints at consecutive vertices, V₄ and V₁, of the square. FIG. 7B exemplifies arc segments, S1-S4, as concave arcs.

After each of the arc segments are constructed, the dimple plan shape of the present invention is generated (step 105). FIG. 8 shows the final dimple plan shape constructed from arc segments, S1-S4, defined in FIG. 7B. In particular, FIG. 8 illustrates a curvilinear dimple plan shape 20 (represented by bold line) contemplated by the present invention. Specifically, FIG. 8 shows a concave dimple plan shape defined by circular arc segments and created from a square (4-sided polygon).

In still another embodiment, the process described above in FIG. 1 may be applicable to designing dimple plan shapes having both concave and convex arc segments. Indeed, the process may be adjusted to design a dimple plan shape having a random combination of both concave and convex arcs. In another embodiment, the process may be adjusted to design a dimple plan shape having alternating convex arcs and concave arcs.

After the dimple plan shape has been generated, at step 106, the plan shape can be used in designing geometries for dimple patterns of a golf ball. For example, the plan shapes generated in accordance with the present invention can be imported into a CAD program and used to define dimple geometries and tool paths for fabricating tooling for golf ball manufacture. The various dimple geometries can then be used in constructing dimple patterns that provide surface textures with unique appearances and improved aerodynamic characteristics.

At step 107, the resulting dimple pattern can be transformed to the outer surface of a golf ball. Similarly, the negative of the resulting dimple pattern may be used to form the interior surface of the cavity of a golf ball mold. For example, the negative of the resulting golf ball dimple pattern can be applied to the interior of a golf ball mold, which can then be used in an injection molding, compression molding, or casting process to form a cover layer comprising the golf ball dimple pattern.

Dimple Patterns & Packing

The golf ball dimples of the present invention may be tailored to maximize surface coverage uniformity and packing efficiency by altering the plan shape of the dimple. For example, in one embodiment, the convex and concave edges

of the dimple plan shapes according to the present invention can be designed such that the dimples are packed more closely together to reduce the width of the land portions adjacent to each dimple. In this aspect, each individual dimple may have a different plan shape so that the space between each dimple can be reduced. Thus, the surface edges of the dimples of the present invention allow for maximizing the dimple coverage on the surface of a golf ball by reducing the land portion located between adjacent dimples.

In another embodiment, the golf ball dimple plan shapes of the present invention can be tailored to maximize surface coverage uniformity and packing efficiency by selecting a regular n-sided polygon having a number of sides that is equivalent to the number of neighboring dimples. For example, if the dimple plan shape is constructed using a regular polygon having 5 sides, the present invention contemplates that the dimple will be surrounded by 5 neighboring dimples. In another embodiment, the number of sides of the regular polygon is a scalar multiple of the number of neighboring dimples. For example, if the number of neighboring dimples is 4, the present invention contemplates a dimple plan shape created from a regular polygon having 8 or 12 sides.

FIGS. 9-11 demonstrate various dimple patterns created in accordance with the present invention. In particular, FIG. 9 illustrates a golf ball dimple pattern 110 made up of hexagonal alternating convex/concave plan shapes 115. Indeed, FIG. 9 illustrates dimple plan shapes 115 defined by alternating convex/concave arcs and created from a 6-sided regular polygon (i.e., hexagon). In addition, FIG. 10 illustrates a golf ball dimple pattern 120 made up of heptagonal concave plan shapes 125. FIG. 10 illustrates dimple plan shapes 125 defined by concave arcs and created from a 7-sided regular polygon (i.e., heptagon). Further, FIG. 11 illustrates a golf ball dimple pattern 130 made up of pentagonal concave plan shapes 135. For example, FIG. 11 shows dimple plan shapes 135 defined by concave arcs and created from a 5-sided regular polygon (i.e., pentagon). As demonstrated in FIGS. 9-11, the present invention provides for the possibility of interdigitation amongst neighboring dimples, a characteristic not possible with conventional circular dimples. This creates the opportunity for additional dimple packing arrangements and dimple distribution on the golf ball surface.

As discussed above, the present invention contemplates dimple plan shapes defined by convex arc segments and created from a three- or four-sided polygon, e.g., a triangle or a square. Such convex dimple plan shapes of the present invention may be utilized in various dimple patterns. For example, in some embodiments, the dimple patterns of the present invention may utilize only square convex dimple plan shapes. In other embodiments, the dimple patterns of the present invention may utilize only triangular convex dimple plan shapes. In other embodiments, the dimple patterns may utilize a combination of square and triangular convex dimple plan shapes. In this aspect, the dimple patterns may include about 1 to about 99 percent of the dimples created from square convex dimple plan shapes with the remainder of the dimples created from triangle convex dimple plan shapes. For example, a suitable dimple pattern may include about 10 to about 90 percent of the dimples created from square convex dimple plan shapes with the remainder of the dimples created from triangle convex dimple plan shapes.

In this aspect, the opposing hemispheres of the golf balls may have the same or different dimple patterns/layouts. The

specific arrangement or packing of the dimples within the hemispheres may vary. For example, each hemisphere may include a base pattern that is rotated about the polar axis and which forms the overall dimple pattern. In other embodiments, each hemisphere may be composed of a single base pattern that is not rotated about the polar axis. The dimples arranged in each hemisphere may be of varying designs and dimensions. For example, each hemisphere may be composed of dimples having square and triangular convex plan shapes and varying profile shapes, dimple diameters, plan shape perimeter ratios, plan shape area ratios, and maximum absolute distances (sagittas).

In some embodiments, the dimple patterns of the present invention may be composed of dimples having the same plan shape type and having identical or differing dimensions. For instance, the dimple patterns may be composed of a number of triangular convex plan shapes having varying or identical equivalent dimple diameters (as defined below), depths, plan shape perimeter ratios, plan shape area ratios, and maximum absolute distances (sagittas). In another embodiment, the dimple patterns of the present invention may be composed of dimples having different plan shape types, where each plan shape type has identical or differing dimensions.

FIGS. 20 and 21 demonstrate dimple patterns utilizing the triangular and square convex dimple plan shapes of the present invention. FIG. 20 illustrates a golf ball dimple pattern made up of a combination of triangular and square convex dimple plan shapes. As shown in FIG. 20, the golf ball dimple pattern 710 is composed of curvilinear convex plan shapes created from a regular three-sided polygon, i.e., an equilateral triangle, 715 and curvilinear convex plan shapes created from a regular four-sided polygon, i.e., a square, 720. In addition, FIG. 21 illustrates a golf ball dimple pattern made up of solely square convex dimple plan shapes. More specifically, as shown in FIG. 21, the golf ball dimple pattern 810 is composed of curvilinear convex plan shapes created from a regular four-sided polygon, i.e., a square, 815. In each of FIGS. 20 and 21, the opposing hemispheres of the golf ball have the same dimple pattern/layout. However, this invention also contemplates golf balls where the opposing hemispheres have different dimple patterns/layouts.

While the dimple plan shapes of the present invention may be used for at least a portion of the dimples on a golf ball, it is not necessary that the dimple plan shapes be used on every dimple of a golf ball. In general, it is preferred that a sufficient number of dimples on the ball are constructed in accordance with the present invention so that the aerodynamic characteristics of the ball may be altered. For example, at least about 30 percent of the dimples on a golf ball include plan shapes according to the present invention. In another embodiment, at least about 50 percent of the dimples on a golf ball include plan shapes according to the present invention. In still another embodiment, at least about 70 percent of the dimples on a golf ball include plan shapes according to the present invention. In yet another embodiment, at least about 90 percent of the dimples on a golf ball include the plan shapes of the present invention. Indeed, 100 percent of the dimples on a golf ball may include the plan shapes of the present invention.

While the present invention is not limited by any particular dimple pattern, dimples having plan shapes according to the present invention are arranged preferably along parting lines or equatorial lines, in proximity to the poles, or along the outlines of a geodesic or polyhedron pattern. Conventional dimples, or those dimples that do not include the plan

shapes of the present invention, may occupy the remaining spaces. The reverse arrangement is also suitable.

In addition, the dimples in each hemisphere should be packed such that the golf ball does not have any dimple free great circles. As will be apparent to those of ordinary skill in the art, a golf ball having no "dimple free great circles" refers to a golf ball having an outer surface that does not contain a great circle which is free of dimples.

Suitable dimple patterns include, but are not limited to, polyhedron-based patterns (e.g., tetrahedron, icosahedron, octahedron, dodecahedron, icosidodecahedron, cuboctahedron, and triangular dipyramid), phyllotaxis-based patterns, spherical tiling patterns, and random arrangements. In one embodiment, the dimples are arranged according to a spherical tiling pattern. For example, the dimples of the present invention may be arranged according to spherical tiling patterns described in U.S. Pat. No. 8,029,388 and U.S. Publication No. 2013/0065708, the entire disclosures of which are incorporated by reference herein.

The dimple patterns of the present invention may be of any count. In one embodiment, the dimple count ranges from about 300 to about 400. In another embodiment, the dimple count is about 312. In still another embodiment, the dimple count is about 330, for example, about 332. In yet another embodiment, the dimple count is about 392. In addition, the dimple pattern may include any number of dimple sizes. In one embodiment, the number of dimple sizes range from about 1 to about 30. In another embodiment, the number of dimple sizes range from about 5 to about 20.

Dimple Patterns Having Cohesively Integrated Dimples

The present invention also contemplates dimple patterns composed of cohesively integrated dimples having the disclosed plan shapes. As discussed above, the dimples of the present invention have a curvilinear plan shape defined by at least three convex and/or concave arcs. The term, "cohesively integrated dimples," refers to an arrangement of adjacent dimples having the disclosed plan shapes where at least one arc edge of the plan shape of a first dimple is adjacent to an arc edge of the plan shape of a second dimple and the two adjacent arc edges are unified. In other words, the two adjacent arc edges are substantially equal in radius, have opposite concavity, and maintain a pre-determined maximum integration distance. The cohesively integrated dimples of the present invention provide improved packing efficiency. For example, the unified edges of the dimple plan shapes according to the present invention provide integrated or opposing concavity, which allows for the dimples to be packed more closely together to reduce the width of the land portions adjacent to each dimple.

In one embodiment, the cohesively integrated dimples of the present invention include adjacent edges that are unified. In this aspect, to be considered "unified," the adjacent edges have opposite concavity. That is, one of the adjacent arc edges curves inward while the opposing adjacent arc edge curve outwards. For example, if the dimple edge of the first dimple is a concave arc, the adjacent dimple edge of the second dimple should be a convex arc. Similarly, if the dimple edge of the first dimple is a convex arc, the adjacent dimple edge of the second dimple should be a concave arc. The concavity of the arcs may also be referred to as "concave-in" (which is intended to refer to concave arcs) and "concave-out" (which is intended to refer to convex arcs). In this aspect, the concavity of the dimple edge of the first dimple is different from the concavity of the adjacent dimple edge of the second dimple.

FIG. 25 shows an example of a dimple pair where the adjacent edges are unified and have opposite concavity. As shown in FIG. 25, the two dimples have adjacent edges, 151 and 152. The edge of the first dimple 151 is a concave arc and the adjacent edge of the second dimple is a convex arc 152. In other words, the edge of the first dimple 151 is concave-in and the adjacent edge of the second dimple is concave-out relative to the centroid of the dimple plan shape. The difference in concavity allows for the adjacent edges to be unified.

In another embodiment, to be considered "unified," the two adjacent edges must have a pre-determined maximum integration distance ("MID"). The MID represents the maximum distance between the two adjacent edges (i.e., the dimple edge of the first dimple and the adjacent dimple edge of the second dimple). To determine the MID between the two adjacent edges, the center of the arc forming the concave edge is identified. For instance, in the pair of adjacent edges shown in FIG. 25, the first dimple has the concave edge (represented by 151). The center of the concave arc that forms edge 151 is determined according to the methods described above. In FIG. 25, the center of the concave arc that forms the edge 151 is represented by 153.

Upon determination of the location of the center of the arc forming the concave edge, three reference lines are drawn that are utilized in calculating the MID. In one embodiment, the first reference line is drawn from the center of the concave arc (as determined from above) to the center point on the concave edge. In this aspect, the first reference line should intersect the adjacent convex edge of the opposing dimple without intersecting any other dimple edges first. For instance, as shown in FIG. 25, the first reference line 154 extends from the center of the concave arc (represented by 153) to the center point on the concave edge 151, which is represented by 154a. The first reference line 154 intersects the adjacent convex edge 152. The second reference line is drawn from the center of the concave arc (as determined from above) to a first vertex of the concave edge. In some embodiments, the first vertex represents the top vertex of the concave edge. As demonstrated in FIG. 25, the second reference line 155 extends from the center of the concave arc (represented by 153) to the top vertex of the concave edge 151, which is represented by 155a. The third reference line 156 is drawn from the center of the concave arc (as determined from above) to a second vertex of the concave edge. In some embodiments, the second vertex represents the bottom vertex of the concave edge. As shown in FIG. 25, the third reference line 156 extends from the center of the concave arc (represented by 153) to the bottom vertex of the concave edge 151, which is represented by 156a.

The MID between the two adjacent edges (i.e., the dimple edge of the first dimple and the adjacent dimple edge of the second dimple) is determined from the reference lines. In one embodiment, if the adjacent convex edge of the opposing dimple only intersects the first reference line, the MID between the two adjacent edges is the distance between the center point on the concave edge and the point of intersection between the first reference line and the adjacent convex edge of the opposing dimple. While the adjacent convex edge 152 in FIG. 25 does not intersect only the first reference line 153, for exemplary purposes, if the adjacent convex edge 152 intersected only the first reference line 153, the MID would be the distance between the center point on the concave edge 154a and the point of intersection between the first reference line 154 and the adjacent convex edge 152 which is represented by 157.

In another embodiment, if the adjacent convex edge of the opposing dimple intersects the first reference line in addition to the second reference line and/or the third reference line, the MID between the two adjacent edges is the largest of the following three distances:

- i. the distance between the center point on the concave edge and the point of intersection between the first reference line and the adjacent convex edge of the opposing dimple;
- ii. the distance between the first vertex of the concave edge and the point of intersection between the second reference line and the adjacent convex edge of the opposing dimple; or
- iii. the distance between the second vertex of the concave edge and the point of intersection between the third reference line and the adjacent convex edge of the opposing dimple.

For instance, in FIG. 25, the adjacent convex edge 152 of the opposing dimple intersects the first reference line 154, the second reference line 155, and the third reference line 156. Accordingly, the MID between the two adjacent edges in FIG. 25 is the largest of:

- i. the distance between the center point on the concave edge 154a and the point of intersection 157 between the first reference line 154 and the adjacent convex edge of the opposing dimple 152;
- ii. the distance between the first vertex of the concave edge 155a and the point of intersection 158 between the second reference line 155 and the adjacent convex edge of the opposing dimple 152; or
- iii. the distance between the second vertex of the concave edge 156a and the point of intersection 159 between the third reference line 156 and the adjacent convex edge of the opposing dimple 152.

The above-described procedure for calculating the MID between two adjacent edges should be repeated for each dimple edge that is to be unified. For instance, if a dimple has two unified edges, the above-described procedure should be utilized to determine the MID between the first pair of adjacent edges and the second pair of adjacent edges. Likewise, if a dimple has three unified edges, the above-described procedure should be utilized to determine the MID between the first pair of adjacent edges, the second pair of adjacent edges, and the third pair of adjacent edges.

In this aspect, to consider the two adjacent edges unified, the MID between the two adjacent edges (i.e., the concave dimple edge and the adjacent convex dimple edge) is less than or equal to about 0.020 inches. In another embodiment, the MID between the unified adjacent edges is less than or equal to about 0.010 inches. In still another embodiment, the MID between the unified adjacent edges is less than or equal to about 0.005 inches. In yet another embodiment, the MID between the unified adjacent edges is less than or equal to about 0.0025 inches. However, as will be apparent to one of ordinary skill in the art, the MID must be greater than zero. In another embodiment, the MID between the unified adjacent edges ranges from about 0.0025 inches to about 0.020 inches. For example, the MID between the unified adjacent edges ranges from about 0.005 inches to about 0.010 inches.

In another embodiment, the adjacent edges have substantially equal arc edge radii. The term, "arc edge radius," refers to the radius of each of the arc edges of the disclosed curvilinear plan shapes. For example, each adjacent edge may have an arc edge radius that is greater than twice the inradius of the base polygon and less than five times the inradius of the base polygon. In another embodiment, each adjacent edge may have an arc edge radius that is greater

than three times the inradius of the base polygon and less than five times the inradius of the base polygon.

As used herein, "substantially equal arc edge radii" means each radius measurement differs by less than 0.10 inches. In 5 another embodiment, "substantially equal arc edge radii" means each radius measurement differs by less than about 0.08 inches. In still another embodiment, "substantially equal arc edge radii" means each radius measurement differs by less than about 0.05 inches. In yet another embodiment, 10 "substantially equal arc edge radii" means each radius measurement differs by less than about 0.01 inches. In another embodiment, the adjacent edges have identical radii.

In still another embodiment, each of the adjacent edges maintains a maximum absolute distance or sagitta. The 15 maximum absolute distance ("d_{max}"), as defined above, represents the maximum distance between the circular arc and the base polygon. Each of the unified adjacent edges has a d_{max} of about 0.005 inches to about 0.030 inches. In another embodiment, each of the unified adjacent edges has a d_{max} of about 0.010 inches to about 0.025 inches. In yet 20 another embodiment, each of the unified adjacent edges has a d_{max} of about 0.015 inches to about 0.020 inches.

In one embodiment, the unified adjacent edges have the same maximum absolute distance. In another embodiment, the unified adjacent edges have different maximum absolute distances. In this aspect, the difference between the maximum absolute distances of each of the two adjacent edges should be less than or equal to about 0.01 inches. In another embodiment, the difference between the maximum absolute distances of each of the two adjacent edges should be less than or equal to about 0.005 inches. In still another embodiment, the difference between the maximum absolute distances of each of the two adjacent edges should be less than or equal to about 0.0025 inches. In yet another embodiment, 30 the difference between the maximum absolute distances of each of the two adjacent edges should be less than or equal to about 0.0015 inches.

Any of the disclosed dimple plan shapes may have unified 40 adjacent edges as discussed above. That is, cohesively integrated dimples of the present invention may include any of the disclosed dimples having a curvilinear plan shape defined by at least three convex and/or concave arcs. For example, in one embodiment, the cohesively integrated dimples may include dimples having a curvilinear plan shape defined by three convex and/or concave arcs. In another embodiment, the cohesively integrated dimples may include dimples having a curvilinear plan shape defined by four convex and/or concave arcs. In still another embodiment, the cohesively integrated dimples may include dimples having a curvilinear plan shape defined by five convex and/or concave arcs. In yet another embodiment, the cohesively integrated dimples may include dimples having a curvilinear plan shape defined by six or more convex and/or concave arcs.

55 In another embodiment, the cohesively integrated dimples may include combinations of dimples having varying curvilinear plan shapes. For example, the cohesively integrated dimples may be arranged such that a dimple having a curvilinear plan shape defined by three concave arcs has an edge that is unified with an adjacent edge of a curvilinear plan shape defined by four convex arcs.

In one embodiment, each cohesively integrated dimple 60 may include more than one edge that has unified arcs. For instance, a first cohesively integrated dimple may include a first edge that is unified with an adjacent edge of a second dimple and the first dimple may include a second edge that is unified with an adjacent edge of a third dimple. In one

embodiment, the cohesively integrated dimple may include at least two edges that have unified arcs (for example, at least two unified edges). In another embodiment, the cohesively integrated dimple may include at least three edges that have unified arcs (for example, at least three unified edges). In still another embodiment, the cohesively integrated dimple may include at least four edges that have unified arcs (for example, at least four unified edges).

While at least a portion of the dimples on a golf ball are cohesively integrated, it is not necessary that every dimple on the golf ball be cohesively integrated. In one embodiment, less than about 10 percent of the dimples on a golf ball having the disclosed curvilinear plan shapes include at least one edge that has unified arcs (for example, unified edges). In another embodiment, more than about 10 percent of the dimples on a golf ball having the disclosed curvilinear plan shapes may include at least one edge that has unified arcs (for example, unified edges). For instance, at least about 25 percent of the dimples on a golf ball having the disclosed curvilinear plan shapes include at least one edge that has unified arcs (for example, unified edges). In another embodiment, at least about 50 percent of the dimples on a golf ball having the disclosed curvilinear plan shapes include at least one unified edge. In still another embodiment, at least about 75 percent of the dimples on a golf ball having the disclosed curvilinear plan shapes include at least one unified edge. In yet another embodiment, at least about 90 percent of the dimples on a golf ball having the disclosed curvilinear plan shapes include at least one unified edge. Indeed, 100 percent of the dimples on a golf ball having the disclosed curvilinear plan shapes may include at least one unified edge.

In this aspect, the present invention contemplates dimple patterns composed of dimples having the disclosed curvilinear plan shapes where at least about 10 percent of all edges defined by circular arcs are unified. In another embodiment, the present invention contemplates dimple patterns composed of dimples having the disclosed curvilinear plan shapes where at least about 25 percent of all edges defined by circular arcs are unified. In still another embodiment, the present invention contemplates dimple patterns composed of dimples having the disclosed curvilinear plan shapes where at least about 50 percent of all edges defined by circular arcs are unified. In yet another embodiment, the present invention contemplates dimple patterns composed of dimples having the disclosed curvilinear plan shapes where at least about 75 percent of all edges defined by circular arcs are unified. In another embodiment, the present invention contemplates dimple patterns composed of dimples having the disclosed curvilinear plan shapes where at least about 90 percent of all edges defined by circular arcs are unified.

FIGS. 27 and 29 demonstrate dimple patterns composed of cohesively integrated dimples having the disclosed plan shapes. That is, FIGS. 27 and 29 illustrate dimple patterns of the present invention that are composed of a plurality of dimples having curvilinear plan shapes defined by at least three convex and/or concave arcs and having unified edges. FIG. 27 shows an arrangement of four dimples having the disclosed plan shapes and unified edges (represented by 900) in a dimple pattern on a golf ball with dimples having circular plan shapes. Each arrangement 900 includes a center dimple having three edges defined by concave circular arcs where all three edges are unified and three surrounding dimples, each having three edges defined by convex circular arcs where only one edge is unified.

FIG. 29 shows a dimple pattern composed entirely of dimples having the disclosed plan shapes (for example, plan

shapes defined by circular arcs). The dimple pattern shown in FIG. 29 (represented by 940) includes dimples having three edges defined by convex circular arcs (represented by 935). The dimple pattern 940 also includes dimples having four edges defined by concave circular arcs (represented by 936) and dimples having four edges defined by convex circular arcs (represented by 937). Each of the four edges of dimples 936 and 937 are unified.

Dimple Dimensions

10 The dimples on the golf balls of the present invention may comprise any width, depth, depth profile, edge angle, or edge radius and the patterns may comprise multitudes of dimples having different widths, depths, depth profiles, edge angles, or edge radii. Since the plan shape perimeters of the 15 present invention are noncircular, the plan shapes are defined by an effective dimple diameter which is twice the average radial dimension of the set of points defining the plan shape from the plan shape centroid. For example, in one embodiment, dimples according to the present invention 20 have an effective dimple diameter within a range of about 0.050 inches to about 0.300 inches. In another embodiment, the dimples have an effective dimple diameter of about 0.100 inches to about 0.250 inches. In still another embodiment, the dimples have an effective dimple diameter of 25 about 0.110 inches to about 0.225 inches. In yet another embodiment, the dimples have an effective dimple diameter of about 0.125 inches to about 0.200 inches.

The dimples of the present invention also have an equivalent dimple diameter. As used herein, "equivalent dimple diameter" is defined as the equivalent circular spherical dimple diameter equal to the specific curvilinear dimple plan shape area. The equivalent dimple diameter may be calculated according to the following formula:

$$d_e = 2\sqrt{\frac{A}{\pi}}$$

35 where d_e is the equivalent dimple diameter and A is the plan shape area of the curvilinear dimple. In one embodiment, the equivalent dimple diameter is at least about 0.08 inches, about 0.09 inches, about 0.010 inches, or about 0.110 inches. In another embodiment, the equivalent dimple diameter is about 0.22 inches or less, about 0.21 inches or less, about 0.20 inches or less, or about 0.19 inches or less. For example, when the dimples have square and triangular convex dimple plan shapes, the dimples may have equivalent dimple diameters ranging from about 0.080 inches to about 0.220 inches. In another embodiment, the dimples may have equivalent dimple diameters ranging from about 0.090 inches to about 0.210 inches. In still another embodiment, the dimples may have equivalent dimple diameters ranging from about 0.100 inches to about 0.200 inches. In yet another embodiment, the dimples may have equivalent dimple diameters ranging from about 0.110 inches to about 0.190 inches.

60 The surface depth for dimples of the present invention is within a range of about 0.003 inches to about 0.025 inches. In one embodiment, the surface depth is about 0.005 inches to about 0.020 inches. In another embodiment, the surface depth is about 0.006 inches to about 0.017 inches.

65 The dimples of the present invention have a plan shape perimeter ratio. The plan shape perimeter ratio is defined as the ratio of the plan shape perimeter to that of the regular n -sided polygon perimeter. The perimeter is defined as the distance around a two-dimensional shape, and thus, the

length of the boundary line defining the plan shape. In one embodiment, dimples of the present invention have a plan shape perimeter ratio of less than 1.10. In another embodiment, the dimples of the present invention have a plan shape perimeter ratio of less than 1.07. In still another embodiment, the dimples of the present invention have a plan shape perimeter ratio of less than 1.05.

For example, when the dimples have triangular convex dimple plan shapes, the dimples may have a plan shape perimeter ratio of less than 1.10, less than 1.05, or less than 1.01. Similarly, when the dimples have square convex dimple plan shapes, the dimples may have a plan shape perimeter ratio of less than 1.10, less than 1.05, or less than 1.01.

The dimples of the present invention also have a plan shape area. By the term, "plan shape area," it is meant the area based on a planar view of the dimple plan shape, such that the viewing plane is normal to an axis connecting the center of the golf ball to the point of the calculated surface depth. In one embodiment, dimples of the present invention have a plan shape area ranging from about 0.0025 in² to about 0.045 in². In another embodiment, dimples of the present invention have a plan shape area ranging from about 0.005 in² to about 0.035 in². In still another embodiment, dimples of the present invention have a plan shape area ranging from about 0.010 in² to about 0.030 in².

The dimples of the present invention are further defined to have a plan shape area ratio. The plan shape area ratio is defined as the ratio of the plan shape area to that of the regular n-sided polygon area. In one embodiment, dimples of the present invention have a plan shape area ratio ranging from about 0.35 to about 1.75. In another embodiment, the plan shape area ratio ranges from about 0.40 to about 1.65. In still another embodiment, the plan shape perimeter ratio ranges from about 0.45 to about 1.55.

For example, when the dimples have triangular convex dimple plan shapes, the dimples may have a plan shape area ratio of greater than 1.0. In one embodiment, when the dimples have triangular convex dimple plan shapes, the dimples may have a plan shape area ratio of equal to or less than 1.75. In another embodiment, the dimples having triangular convex dimple plan shapes may have a plan shape area ratio of equal to or less than 1.65. In still another embodiment, the dimples having triangular convex dimple plan shapes may have a plan shape area ratio of equal to or less than 1.55. In one embodiment, the plan shape area ratio is between 1.0 and 1.75, 1.0 and 1.65, or 1.0 and 1.55.

Similarly, when the dimples have square convex dimple plan shapes, the dimples may have a plan shape area ratio of greater than 1.0. In one embodiment, the dimples having square convex dimple plan shapes have a plan shape area ratio of 1.75 or less, 1.65 or less, or 1.55 or less. For example, the dimples having square convex dimple plan shapes may have a plan shape area ratio of more than 1.0, but no more than 1.75.

Further, dimples of the present invention have a dimple surface volume. By the term, "dimple surface volume," it is meant the total volume encompassed by the dimple shape and the surface of the golf ball. FIGS. 12A and 12B illustrate graphical representations of dimple surface volumes contemplated for dimples produced in accordance with the present invention. For example, FIGS. 12A and 12B demonstrate contemplated dimple surface volumes over a range of plan shape areas. In one embodiment, dimples produced in accordance with the present invention have a plan shape area and dimple surface volume falling within the ranges shown in FIG. 12A. For example, a dimple having a plan

shape area of about 0.01 in² may have a surface volume of about 0.20×10⁻⁴ in³ to about 0.50×10⁻⁴ in³. In another embodiment, a dimple having a plan shape area of about 0.025 in² may have a surface volume of about 0.80×10⁻⁴ in³ to about 1.75×10⁻⁴ in³. In still another embodiment, a dimple having a plan shape area of about 0.030 in² may have a surface volume of about 1.20×10⁻⁴ in³ to about 2.40×10⁻⁴ in³. In yet another embodiment, a dimple having a plan shape area of about 0.045 in² may have a surface volume of about 2.10×10⁻⁴ in³ to about 4.25×10⁻⁴ in³.

In another embodiment, dimples produced in accordance with the present invention have a plan shape area and dimple surface volume falling within the ranges shown in FIG. 12B. For example, a dimple having a plan shape area of about 0.01 in² may have a surface volume of about 0.25×10⁻⁴ in³ to about 0.35×10⁻⁴ in³. In another embodiment, a dimple having a plan shape area of about 0.025 in² may have a surface volume of about 1.10×10⁻⁴ in³ to about 1.45×10⁻⁴ in³. In yet another embodiment, a dimple having a plan shape area of about 0.030 in² may have a surface volume of about 1.40×10⁻⁴ in³ to about 1.90×10⁻⁴ in³.

In still another embodiment, when the dimples have square or triangular convex dimple plan shapes, the dimples may have a plan shape area and dimple surface volume falling within the ranges shown in FIG. 22. FIG. 22 illustrates a graphical representation of dimple surface volumes contemplated for dimples having square and triangular convex dimple plan shapes. The dimple volumes should be less than the upper limit volume calculated by

$$V_s = -0.0464A^2 + 0.0135A - 1.00 \times 10^{-5}$$

and greater than the lower limit calculated by

$$V_s = 0.0703A^2 + 0.0016A - 3.00 \times 10^{-6}$$

where A is the dimple plan shape area. In one embodiment, the dimple plan shape area (A) may range from 0.0025 in² to 0.045 in². In another embodiment, the dimple plan shape area (A) may range from 0.0050 in² to 0.035 in². In yet another embodiment, the dimple plan shape area (A) may range from 0.0050 in² to 0.030 in². In still another embodiment, the dimple plan shape area (A) may range from 0.0075 in² to 0.020 in². In yet another embodiment, the dimple plan shape area (A) may range from 0.010 in² to 0.015 in². In still another embodiment, the dimple plan shape area (A) may range from 0.010 in² to 0.030 in².

Based on the above equations and the contemplated dimple plan shape areas, the surface volumes of dimples having square or triangular convex dimple plan shapes may range from about 0.014×10⁻⁴ in³ to about 5.035×10⁻⁴ in³. In another embodiment, the surface volumes may range from about 0.50×10⁻⁴ in³ to about 4.50×10⁻⁴ in³. For example, the surface volume may range from about 0.50×10⁻⁴ in³ to about 3.0×10⁻⁴ in³ or about 0.50×10⁻⁴ in³ to about 2.0×10⁻⁴ in³. In still another embodiment, the surface volumes may range from about 1.5×10⁻⁴ in³ to about 4.0×10⁻⁴ in³. In yet another embodiment, the surface volumes may range from about 2.0×10⁻⁴ in³ to about 3.5×10⁻⁴ in³.

Dimple Profile

In addition to varying the size of the dimples, the cross-sectional profile of the dimples may be varied. The cross-sectional profile of the dimples according to the present invention may be based on any known dimple profile shape. In one embodiment, the profile of the dimples corresponds to a curve. For example, the dimples of the present invention may be defined by the revolution of a catenary curve about an axis, such as that disclosed in U.S. Pat. Nos. 6,796,912 and 6,729,976, the entire disclosures of which are incorpo-

25

rated by reference herein. In another embodiment, the dimple profiles correspond to polynomial curves, ellipses, spherical curves, saucer-shapes, truncated cones, trigonometric, exponential, frequency, or logarithmic curves and flattened trapezoids. In still another embodiment, the dimples of the present invention may have dimple profiles that are conical. In yet another embodiment, the dimple profiles may be created from a set of mathematical functions including polynomial, exponential, and trigonometric functions or combinations thereof.

The profile of the dimple may also aid in the design of the aerodynamics of the golf ball. For example, shallow dimple depths, such as those in U.S. Pat. No. 5,566,943, the entire disclosure of which is incorporated by reference herein, may be used to obtain a golf ball with high lift and low drag coefficients. Conversely, a relatively deep dimple depth may aid in obtaining a golf ball with low lift and low drag coefficients.

The dimple profile may also be defined by combining a spherical curve and a different curve, such as a cosine curve, a frequency curve or a catenary curve, as disclosed in U.S. Patent Publication No. 2012/0165130, which is incorporated in its entirety by reference herein. In another embodiment, the dimple profile can result from the superposition of three or more different curves. In still another embodiment, one or more of the superposed curves can be a functionally weighted curve, as disclosed in U.S. Patent Publication No. 2013/0172123, which is incorporated in its entirety by reference herein.

Golf Ball Construction

The dimples of the present invention may be used with practically any type of ball construction. For instance, the golf ball may have a two-piece design, a double cover, or two-component dual core construction depending on the type of performance desired of the ball. Other suitable golf ball constructions include solid, wound, liquid-filled, and/or dual cores, and multiple intermediate layers.

Different materials may be used in the construction of the golf balls made with the present invention. For example, the cover of the ball may be made of a thermoset or thermoplastic, a castable or non-castable polyurethane and polyurea, an ionomer resin, balata, or any other suitable cover material known to those skilled in the art. Conventional and non-conventional materials may be used for forming core and intermediate layers of the ball including polybutadiene and other rubber-based core formulations, ionomer resins, highly neutralized polymers, and the like.

EXAMPLES

The following non-limiting examples demonstrate golf ball dimple plan shapes made in accordance with the present invention. The examples are merely illustrative of the preferred embodiments of the present invention, and are not to be construed as limiting the invention, the scope of which is defined by the appended claims.

Examples 1-5 demonstrate various curvilinear dimple plan shapes defined by circular arcs that are derived from regular n-sided polygons. As demonstrated by the following examples, the present invention provides for a number of different visually distinct dimple plan shapes and surface textures.

Example 1

The following example illustrates a golf ball dimple plan shape produced in accordance with the present invention. In

26

particular, FIG. 13 illustrates a concave plan shape 30 (represented by bold line) derived from a regular five-sided polygon, or a pentagon, 202. As shown in FIG. 13, the plan shape 30 is defined by five concave arcs originating from centers C1-C5 and having equal radii, r_i , with respective indices 1 through 5. The circumradius 201 and inradius 200 for the pentagon 202 are illustrated as dashed lines centered about the origin, O. The dimple plan shape 30 is further defined as having a plan shape perimeter ratio of 1.0045 and a plan shape area ratio of 0.9206.

Example 2

The following example illustrates a golf ball dimple plan shape produced in accordance with the present invention. In particular, FIG. 14 illustrates a convex plan shape 40 (represented by bold line) derived from a regular six-sided polygon, or a hexagon, 302. As shown in FIG. 14, the plan shape 40 is defined by six convex arcs originating from centers C1-C6 and having equal radii, r_i , with respective indices 1 through 6. The circumradius 301 and inradius 300 for the hexagon 302 are illustrated as dashed lines centered about the origin, O. The dimple plan shape 40 is further defined as having a plan shape perimeter ratio of 1.0107 and a plan shape area ratio of 1.0976.

Example 3

The following example illustrates a golf ball dimple plan shape produced in accordance with the present invention. In particular, FIG. 15 illustrates a plan shape 50 (represented by bold line) created from a random arrangement of convex and concave arcs derived from a regular five-sided polygon, or a pentagon, 402. As shown in FIG. 15, the plan shape 50 is defined by five convex/concave arcs originating from centers C1-C5 and having equal radii, r_i , with respective indices 1 through 5. The circumradius 401 and inradius 400 for the pentagon 402 are illustrated as dashed lines centered about the origin, O. The dimple plan shape 50 is further defined as having a plan shape perimeter ratio of 1.0056 and a plan shape area ratio of 1.0177.

Example 4

The following example illustrates a golf ball dimple plan shape produced in accordance with the present invention. In particular, FIG. 16 illustrates a plan shape 60 (represented by bold line) created from alternating convex and concave arcs derived from a regular six-sided polygon, or a hexagon, 502. As shown in FIG. 16, the plan shape 60 is defined by six alternating convex and concave arcs originating from centers C1-C6 and having equal radii, r_i , with respective indices 1 through 6. The circumradius 501 and inradius 500 for the hexagon 502 are illustrated as dashed lines centered about the origin, O. The dimple plan shape 60 is further defined as having a plan shape perimeter ratio of 1.0079 and a plan shape area ratio of 1.000. Dimple plan shapes in accordance with this embodiment of the present invention are limited to regular n-sided polygons having an even number of sides.

Example 5

The following example illustrates a golf ball dimple plan shape produced in accordance with the present invention. In particular, FIG. 17 illustrates a plan shape 70 (represented by bold line) created from convex arcs having different radii from a regular four-sided polygon, or a square, 602. As

shown in FIG. 17, the plan shape 70 is defined by convex arcs of different radii originating from centers C1-C4 and having radii, r_i , with respective indices 1 through 4. In this embodiment, $r_1=r_3$ and $r_2=r_4$. The circumradius 601 and inradius 600 for the square 602 are illustrated as dashed lines centered about the origin, O. The dimple plan shape 70 is further defined as having a plan shape perimeter ratio of 1.0178 and a plan shape area ratio of 1.2144.

Example 6

The following example illustrates a golf ball dimple pattern contemplated by the present invention. More particularly, the following example illustrates a dimple base pattern utilizing square and triangular convex plan shapes of varying sizes. FIG. 23 shows a dimple base pattern with curvilinear convex plan shapes created from regular three- and four-sided polygons, i.e., an equilateral triangle and a square, respectively. The dimple base pattern of FIG. 23 may be used in a golf ball pattern having 302 dimples. While FIG. 23 illustrates the segment dimple pattern, FIG. 20 generally illustrates the overall golf ball dimple pattern.

Referring to FIG. 23, the dimples having plan shapes based on three circular arcs or the triangular convex plan shapes are represented by letter IDs: A, B, C, D, and E. Dimples A, B, C, D, and E have a plan shape perimeter ratio of 1.0245 and a plan shape area ratio of 1.4469 with equivalent dimple diameters ranging from about 0.105 inches to about 0.195 inches. In addition, dimples A, B, C, D, and E have maximum absolute distances, or sagittas, ranging from about 0.011 inches to about 0.021 inches.

The dimples having plan shapes created from four circular arcs or the square convex plan shapes are represented by letter ID: F. Dimples F have a plan shape perimeter ratio of 1.0170 and a plan shape area ratio of 1.2144 with an equivalent dimple diameter of about 0.210 inches. In addition, dimples F have a maximum absolute distance, or sagitta, of about 0.013 inches.

Although any dimple profile or profiles can be used, as discussed above, the ideal dimple volumes should remain within the preferred range defined in FIG. 22. Furthermore, for optimal flight performance, the dimple volumes should be between about 0.5×10^{-4} in³ and 2×10^{-4} in³ depending on dimple plan shape area.

Example 7

The following example illustrates another golf ball dimple pattern contemplated by the present invention. In particular, the following example illustrates a dimple base pattern utilizing square convex plan shapes. FIG. 24 shows a dimple base pattern with curvilinear convex plan shapes created from regular four-sided polygons, i.e., a square. The dimple base pattern of FIG. 24 may be used in a golf ball pattern having 312 dimples. While FIG. 24 illustrates the segment dimple pattern, FIG. 21 illustrates the overall golf ball dimple pattern.

Referring to FIG. 24, six types of dimples having four circular arcs (square dimples), which account for all of the plan shapes within the pattern, are represented by A, B, C, D, E, F, and G. In this example, dimples A, B, C, D, E, F, and G are defined to be identical regardless of their equivalent dimple diameters. Each plan shape within the dimple pattern has a plan shape perimeter ratio of 1.0068 and a plan shape area ratio of 1.1347 with equivalent dimple diameters ranging from about 0.110 inches to about 0.175 inches. Additionally, dimples A, B, C, D, E, F, and G have maxi-

mum absolute distances, or sagittas, ranging from about 0.005 inches to about 0.007 inches.

Although any dimple profile or profiles can be used, as discussed above, the ideal dimple volumes should remain within the preferred range defined in FIG. 22. Furthermore, for optimal flight performance, the dimple volumes should be between about 0.5×10^{-4} in³ and 2×10^{-4} in³ depending on dimple plan shape area.

10

Example 8

The following example illustrates a dimple pattern of the present invention having cohesively integrated dimples. FIGS. 26A and 26B show an arrangement of four dimples having the disclosed plan shapes and unified edges (represented by 900). The center dimple 901 has a plan shape composed of three concave circular arcs. The center dimple 901 is surrounded by three adjacent dimples 902, 903, 904. Each of the adjacent dimples 902, 903, 904 has a plan shape composed of three convex circular arcs. All of the dimples in this example have the same maximum distance between the circular arc and the base polygon (d_{max}) of approximately 0.015 inches.

When determining the maximum integration distance (MID) in this example, the center of the arc forming the concave edge is identified. In FIG. 26B, the center of the arc forming the concave edge of dimple 901 is represented by 905. The first reference line 906 is drawn from the center of the concave arc 905 to the center point on the concave edge of the center dimple 901. The second reference line 907 is drawn from the center of the concave arc 905 to a top vertex of the concave edge of the center dimple 901. The third reference line 908 is drawn from the center of the concave arc 905 to a bottom vertex of the concave edge of the center dimple 901. The MID is the same at all three measurement points (909, 910, and 911). In this example, the MID is equal to about 0.010 inches.

As can be seen in FIGS. 26A and 26B, the center dimple 901 has three edges defined by concave circular arcs and all three edges are unified. That is, the center dimple 901 has a first edge that is unified with an adjacent edge of dimple 902, a second edge that is unified with an adjacent edge of dimple 903, and a third edge that is unified with an adjacent edge of dimple 904. However, the other dimples having three edges defined by convex circular arcs 902, 903, 904 include only one unified edge. The remaining edges of dimples 902, 903, 904 are not unified.

FIG. 27 shows the arrangement of the four dimples having the disclosed plan shapes and unified edges (represented by 900) in a dimple pattern on a golf ball with dimples having circular plan shapes. The dimple pattern exemplified in FIG. 27 is composed of 350 dimples. The arrangement of dimples 900 is repeated eight times around the golf ball, equating to 32 dimples having edges defined by circular arcs. Of those 32 dimples, eight of the dimples have three edges defined by concave circular arcs and 24 of the dimples have three edges defined by convex circular arcs. In other words, a total of 96 dimple edges on the golf ball are defined by circular arcs. Of the 96 total arc edges, 48 arc edges are unified as defined by the present invention. Accordingly, approximately 50 percent of the edges defined by circular arcs are unified. Moreover, in relation to the total number of dimples on the golf ball, 9.1 percent of the dimples on the golf ball have at least one unified edge (i.e., 32 dimples out of the total 350

29

dimples). In addition, 100 percent of all dimples having the disclosed curvilinear plan shapes have at least one unified edge.

Example 9

The following example illustrates an arrangement of cohesively integrated dimples according to the present invention. FIGS. 28A and 28B show an arrangement of four dimples having the disclosed plan shapes and unified edges (represented by 920). Two of the dimples 921 and 924 have plan shapes composed of four convex circular arcs. The other two dimples 922 and 923 have plan shapes composed of four concave circular arcs. All of the dimples in this example have the same maximum distance between the circular arc and the base polygon (d_{max}) of approximately 0.017 inches.

When determining the maximum integration distance (MID) in this example, the center of the arc forming the concave edge is identified. In FIG. 28B, the center of the arc forming the concave edge of dimple 922 is represented by 925. The first reference line 926 is drawn from the center of the concave arc 925 to the center point on the concave edge of dimple 922. The second reference line 927 is drawn from the center of the concave arc 925 to a top vertex of the concave edge of dimple 922. The third reference line 928 is drawn from the center of the concave arc 925 to a bottom vertex of the concave edge of dimple 922. The MID is the same at all three measurement points (929, 930, and 931). In this example, the MID is equal to about 0.012 inches.

As can be seen in FIGS. 28A and 28B, the two dimples having plan shapes composed of four convex circular arcs 921 and 924 include two unified edges. That is, dimple 921 has a first edge that is unified with an adjacent edge of dimple 922 and a second edge that is unified with an adjacent edge of dimple 923. Similarly, dimple 924 has a first edge that is unified with an adjacent edge of dimple 922 and a second edge that is unified with an adjacent edge of dimple 923. The two dimples having plan shapes composed of four concave circular arcs 922 and 923 also include two unified edges. Dimple 922 has a first edge that is unified with an adjacent edge of dimple 921 and a second edge that is unified with an adjacent edge of dimple 924. Likewise, dimple 923 has a first edge that is unified with an adjacent edge of dimple 921 and a second edge that is unified with an adjacent edge of dimple 924. In this example, the remaining edges of dimples 921, 922, 923, 924 are not unified.

Example 10

The following example illustrates a dimple pattern of the present invention having cohesively integrated dimples. FIG. 29 shows a dimple pattern composed entirely of dimples having the disclosed plan shapes (for example, plan shapes defined by circular arcs). The dimple pattern shown in FIG. 29 (represented by 940) is composed of 368 dimples. The dimple pattern 940 includes eight dimples each having three edges defined by convex circular arcs. These dimples are represented by 935. The dimple pattern 940 also includes the arrangement of dimples described in Example 9 (shown in the bolded circle in FIG. 29). More particularly, the dimple pattern 940 includes 180 dimples each having four edges defined by concave circular arcs (represented by 936) and 180 dimples each having four edges defined by convex circular arcs (represented by 937). Each of the four edges of dimples 936 and 937 are unified. This equates to 1,464 total dimple edges defined by circular arcs. Of the total number

30

of arc edges, 1,272 edges are unified as defined by the present invention. Accordingly, approximately 87 percent of the edges defined by circular arcs are unified. Moreover, in relation to the total number of dimples on the golf ball, 97.8 percent of the dimples on the golf ball have at least one unified edge (i.e., 360 dimples out of the total 368 dimples).

Notwithstanding that the numerical ranges and parameters setting forth the broad scope of the invention are approximations, the numerical values set forth in the specific examples are reported as precisely as possible. Any numerical value, however, inherently contain certain errors necessarily resulting from the standard deviation found in their respective testing measurements. Furthermore, when numerical ranges of varying scope are set forth herein, it is contemplated that any combination of these values inclusive of the recited values may be used.

The invention described and claimed herein is not to be limited in scope by the specific embodiments herein disclosed, since these embodiments are intended as illustrations of several aspects of the invention. Any equivalent embodiments are intended to be within the scope of this invention. Indeed, various modifications of the invention in addition to those shown and described herein will become apparent to those skilled in the art from the foregoing description. Such modifications are also intended to fall within the scope of the appended claims. All patents and patent applications cited in the foregoing text are expressly incorporated herein by reference in their entirety.

What is claimed is:

1. A golf ball having a substantially spherical surface, comprising:
a plurality of dimples on the spherical surface, wherein at least a portion of the plurality of dimples have a non-isodiametrical plan shape defined by at least three circular arcs, wherein each circular arc defines an edge of the dimple and comprises two discontinuous endpoints that define adjacent vertices of a base polygon, wherein at least one dimple pair in the portion of the plurality of dimples comprises a first dimple having a first edge and a second dimple having a second edge that is adjacent to the first edge, wherein the first edge is defined by a concave circular arc and the second edge is defined by a convex circular arc, and a maximum integration distance between the first edge and the second edge is 0.020 inches or less, and wherein the dimples having a non-isodiametrical plan shape consist of concave-edged dimples and convex-edged dimples, each edge of the concave-edged dimples being defined by a concave circular arc and each edge of the convex-edged dimples being defined by a convex circular arc.
2. The golf ball of claim 1, wherein the first edge and the second edge have substantially equal arc edge radii.
3. The golf ball of claim 1, wherein the first edge and the second edge each have a maximum distance between the circular arc and the base polygon of about 0.005 inches to about 0.030 inches.
4. The golf ball of claim 3, wherein the first edge and the second edge have the same maximum distances.
5. The golf ball of claim 3, wherein the first edge has a first maximum distance, the second edge has a second maximum distance, and the difference between the first maximum distance and the second maximum distance is less than or equal to 0.01 inches.

31

6. The golf ball of claim 1, wherein the maximum integration distance between the first edge and the second edge is 0.010 inches or less.

7. The golf ball of claim 1, wherein the dimples having a non-isodiametrical plan shape consist of dimples having a non-isodiametrical plan shape defined by three or four circular arcs.

8. A golf ball having a substantially spherical surface, comprising:

a plurality of dimples on the spherical surface, wherein at least a portion of the plurality of dimples have a non-isodiametrical plan shape defined by circular arcs, wherein each circular arc defines an edge of the dimple and comprises two discontinuous endpoints that define adjacent vertices of a base polygon, wherein at least one dimple pair in the portion of the plurality of dimples comprises a first dimple having a first edge and a second dimple having a second edge that is adjacent to the first edge, wherein the first edge is defined by a concave circular arc and the second edge is defined by a convex circular arc, and a maximum integration distance between the first edge and the second edge is 0.020 inches or less, and wherein the dimples having a non-isodiametrical plan shape consist of dimples having a non-isodiametrical plan shape defined by three circular arcs.

9. The golf ball of claim 8, wherein the first edge and the second edge have substantially equal arc edge radii.

10. The golf ball of claim 8, wherein the maximum integration distance between the first edge and the second edge is 0.010 inches or less.

32

11. The golf ball of claim 8, wherein the maximum integration distance between the first edge and the second edge is 0.005 inches or less.

12. A golf ball having a substantially spherical surface, comprising:

a plurality of dimples on the spherical surface, wherein at least a portion of the plurality of dimples have a non-isodiametrical plan shape defined by circular arcs, wherein each circular arc defines an edge of the dimple and comprises two discontinuous endpoints that define adjacent vertices of a base polygon, wherein at least one dimple pair in the portion of the plurality of dimples comprises a first dimple having a first edge and a second dimple having a second edge that is adjacent to the first edge, wherein the first edge is defined by a concave circular arc and the second edge is defined by a convex circular arc, and a maximum integration distance between the first edge and the second edge is 0.020 inches or less, and wherein the dimples having a non-isodiametrical plan shape consist of dimples having a non-isodiametrical plan shape defined by four circular arcs.

13. The golf ball of claim 12, wherein the first edge and the second edge have substantially equal arc edge radii.

14. The golf ball of claim 12, wherein the maximum integration distance between the first edge and the second edge is 0.010 inches or less.

15. The golf ball of claim 12, wherein the maximum integration distance between the first edge and the second edge is 0.005 inches or less.
